Primary Examiner — Selina Sikder(74) *Attorney, Agent, or Firm* — W&KIP(57) **CLAIM**

The ornamental design for an LED controller, as shown and described.

DESCRIPTION

FIG. 1 is a perspective view of an LED controller showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective view thereof; and,

FIG. 9 is an enlarged view of a portion of FIG. 8.

The evenly-broken lines where present illustrate portions of the LED controller that form no part of the claimed design.

1 Claim, 9 Drawing Sheets(56)
